SHOE RACK

Edward E. Weston, Dayton, Ohio; Wellmore B. Turner and W. G. Clark executors of said Edward B. Weston, deceased

Application January 15, 1932. Serial No. 586,813

2 Claims. (Cl. 211—38)

The present invention relates to storage and display apparatus, and has particular application to racks and stands for storing and displaying shoes or similarly shaped articles.

Among the objects of my present invention are to provide an inexpensive storage and display rack or stand, which may be readily manufactured or assembled from relatively few, readily available sheet metal or light weight metal members with a minimum of operations; which may be conveniently shipped and stored in dismantled condition, in which condition it will occupy little space, and may be handled, packaged and merchandised; which may be readily assembled and dismantled by a store-keeper or householder, as with the sole use of a screw-driver; which will readily serve as a shoe rack for merchandising purposes, or storage rack for the home; and which without modification is readily adapted to support and display shoes either for men or for women, of a wide variety of shapes and sizes.

In one embodiment of the invention, the rack or stand includes vertical side members, which may consist of inverted U-shaped flat metal strips or stampings. The ends of the legs of the U serve to support the rack upon the floor.

The shoe-receiving or supporting members of the rack consist of similar strips of metal, bent into rectangles, the ends of which strips are preferably riveted, or otherwise connected, together at one corner of said rectangles. Usually these rectangles are provided with relatively short sides to be attached to said inverted U-members.

The lower edges of these short sides are recessed and the recesses so formed are arranged and spaced, preferably adjacent the corners of the rectangle, as to cooperate with, and fit upon, the screw and nut arrangements connected with the sides of said inverted U-shaped members.

The screw and nut members may be readily tightened, as with a screw-driver, to clamp the transverse rectangular members firmly in position and form a rigid assembly. On the other hand, the screws may be readily loosened upon dismantling.

In the drawing, which shows one embodiment of the present invention,

Fig. 1 shows a top perspective view of the rack assembled.

Fig. 2 shows a side sectional view upon the plane 2—2 of Fig. 1, and

Figs. 3 and 4 show, respectively, the side member and the transverse member of the rack dismantled from the assembly of Fig. 1.

In Figs. 1 to 4, the side members 10 consist of flat strips of metal or stampings, which have been bent to form a U, the side legs 11 of which U, serve to support the rack and to receive the transverse rectangular members 12. The lower ends 13 of the legs 11 are bent outwardly and are flattened at their bottoms to form a firmer support for the rack.

The transverse members 12 are preferably formed of single elongated strips or stampings of metal, which are bent into the form of a rectangle, the ends of which strips are overlapped and riveted, or otherwise, attached, together at 14. The short sides 15 of the rectangular transverse member are provided with recesses 16 on their lower edges adjacent the corners of the rectangle. These recesses fit over, and co-operate with, the nut—screw clamping arrangements 17—27.

In Figure 2 is diagrammatically illustrated the preferred arrangement of shoes upon the rack of the present invention with the heels 18 and 19 projecting beyond the back of the rectangular member 12 and with the depressions 20 and 21 at the instep resting upon the top of the rectangular member 12. The toes 22 and 23 will then rest upon the front of said rectangular member.

As shown, the rectangular members are caused to slant forwardly by positioning the rear screw and nut attachments 17—27, above the corresponding forward screw and nut attachments 17—27. This angle or slope of the rectangular transverse and supporting members 12 may be varied, as may also the number of rectangular members 12 utilized, the spacing between the front and rear of said members, and also the spacing between the legs 11 of the side members. The height of the side members 10 may be increased or decreased to take care of a greater or lesser number of rectangular supports 12.

It will be noted that all the metal strips are so positioned that their sides will be substantially vertical, thus greatly increasing the strength and rigidity of the combined structure, improving its appearance and decreasing the dirt and dust-collecting horizontal surfaces. In the case of the rectangular members 12, this will also enable a relatively easy bending operation, as well as resulting in a more convenient support for the shoe to be displayed or stored.

The shoe rack of the present invention, is clean, sanitary, convenient and saves space. It may be constructed of unbreakable bar steel and finished in attractive colors, such as silver, gold, blue, lavender and rose. It is particularly val-

uable in the modern home where it may be utilized for receiving adults as well as the children's shoes, and where its skeleton construction gives the perfect ventilation, prolonging the life of the 5 shoes. It may be readily placed in any convenient position as, for example, near or against the wall, in the closet, on a shelf, or near the bed.

In assembling, the side U-members are provided with the nut and screw attachments 10 17-27. The transverse supporting members 12 are then assembled with such side members, fitting the recesses 16 over the shanks of the screws 27 inside of the nuts 17. A screw-driver may be then readily applied to the slotted heads of the 15 screws to clamp together the sides 15 and the U-members 10, the nuts being preferably placed sufficiently close to the longer sides of the rectangular member 12 as to be prevented from turning.

20 In one preferred embodiment of assembly, one upright frame is placed in vertical position, and the notches in one of the shelves are fitted onto the shoes in the frame between the nuts and the frame. Thereupon the screws are tightened 25 with a small screw-driver, thus clamping one of the side members and one of the rectangular frames firmly together. After this the notches on the other side of said rectangular frame or shelf are fitted onto the screws of the opposite 30 upright frame, and these screws are then tightened. The upper shelves then may be successively fitted onto their screw connections and tightened in position.

35 The rack may be similarly dismantled by application of a screw-driver to the slotted heads of the screws, the dismantled rack consisting of the two relatively flat transverse members 12, and side members 10, which members may be conveniently tied or wrapped together for merchandising, storage or shipment.

40 It will be noted that the rack consists of but two metal forms, the transverse members 12 and the side members 10 being respectively interchangeable.

45 As shown in Figure 3, the rack arrangement may be conveniently modified so that the rear leg may be split as indicated at 60, in which arrangement the upper rear bolt and nut arrangement 17-27, will serve both as a pivot to permit the leg to be swung into position 61 or 62. Upon shipping or packing, the rear leg is conveniently swung toward the front leg 11 so that the projecting ends 13 will not be of greater 55 width than the distance between the longitudinal front and rear members of the rectangular frames 12. This will enable much more convenient packaging. On the other hand, the rear leg may be moved away from the front leg 11 if it is desired to use a rectangular shelf 12 upon 60 the bottom of the rack, which will have a greater spacing between the front and rear longitudinal members than the upper rectangular frame. In either case, the upper rear bolt and nut arrangement 17-27 conveniently serves to 65 clamp the swinging leg to the side member 10 in any desired position.

In shipping, the various rack members 10 and 12 when dismantled, are conveniently placed between sheets of corrugated packing in which

the bolts and nuts are embedded. This will prevent said bolts and nuts from scratching or marring the various component elements of the rack. To prevent the nuts 17 from falling or being screwed off, the ends of the bolts are preferably buried.

80 While I have illustrated and described a preferred embodiment of my invention, I do not wish to be understood as limiting myself to the specific construction shown except as I may be limited by the process of appended claims.

85 What is claimed is:—

1. A shoe storage rack comprising inverted U-shaped side upright members, each comprising a single strip of metal bent into an inverted J-shaped piece and a rear leg member, which is detachable and pivotally connected by a nut and bolt attachment to the short leg of the J-piece, whereby upon loosening said attachment the rear and front legs may be collapsed together 90 for convenience in shipping and also comprising supporting frame members of rectangular shape with spaced longitudinal bars and end bars, each formed of a single metal strip, the ends of which are connected together along one of the longitudinal bars adjacent one of the corners, said frame members being forwardly and downwardly inclined and said longitudinal bars being spaced apart so that the heel of the shoe will overhang 95 the rear longitudinal bar and be stopped thereby and the toe of the shoe will be supported upon the front bar and project forwardly therebeyond, the end bars of the frame members being each provided with a pair of open recesses in the lower 100 edges thereof adjacent each corner and the side members being provided with openings holding nut and bolt attachments corresponding to said recesses, whereby upon loosening of said bolt and nut attachments, without detachment thereof from the side members, the frame members may 105 be lifted out of position and the rack collapsed for storage and shipment, with the bolt and nut attachment permanently connected to upright members ready to be tightened upon reassembly.

110 2. A shoe storage rack comprising inverted U-shaped side upright members, each comprising a single strip of metal bent into an inverted J-shaped piece and a rear leg member, which is detachable and pivotally connected by a nut and bolt attachment to the short leg of the J-piece, whereby upon loosening said attachment the rear and front legs may be collapsed together 115 for convenience in shipping, and also comprising intermediate shoe-supporting frame members, each frame member consisting of a pair of horizontal bars removably secured at their opposite ends to said upright members, the rear bar of each frame member mounted in a plane above that of its companion front bar and the two bars 120 being spaced apart a distance sufficient to support shoes arranged transversely thereof and inclined downwardly from heel to toe with the heel of each shoe behind the rear of the toe 125 resting upon the front bar, and means for detachably connecting the frame members to the uprights whereby the structure may be knocked down and closely packed for shipment.

130 EDWARD B. WESTON.
